Des. 186,815
Patented Dec. 8, 1959

186,815

REMOTE CONTROL TRANSMITTER

Melvin H. Boldt, Glenview, Ill., assignor to Zenith Radio
Corporation, a corporation of Delaware

Application July 29, 1959, Serial No. 56,973

Term of patent 14 years

(Cl. D26—14)

FIG. 1

FIG. 2

FIG. 3

FIG. 4

FIG. 5

Figure 1 is a perspective view of a remote control transmitter, showing my new design;

Figure 2 is a front view thereof;

Figure 3 is a side view thereof;

Figure 4 is a rear view thereof; and

Figure 5 is a top view thereof.

The bottom of the remote control transmitter is plain.

I claim:

The ornamental design for a remote control transmitter, substantially as shown and described.
